(57) **CLAIM**

The ornamental design for a granulation/mixing machine
with storage cabinet, as shown.

DESCRIPTION

FIG. 1 is a perspective view of the granulation/mixing
machine of the present invention.

FIG. 2 is a front elevation view of the machine.

FIG. 3 is a top plan view of the machine; and,

FIGS. 4 and 5 are elevation views from opposite sides of the
machine.

The broken lines shown in the drawings are for illustrative
purposes only and form no part of the claimed design.
